UNITED STATES PATENT OFFICE.

VICTORINO LORENZO, OF BUENOS AIRES, ARGENTINA.

CHANGEABLE PRICE SIGN.

Application filed April 2, 1924, Serial No. 703,807, and in Argentina April 18, 1922.

This invention relates to a new and improved system of loose letters, figures and characters, in combination with a base or surface to be used as a background for the same, for the purpose of making in a rapid, artistic, economical and easily variable manner, signs and any kind of inscriptions for the exhibition of merchandise, or for other similar uses.

It consists substantially of a convenient collection of characters, letters, figures and the like, drawn on and cut out from any appropriate material such as cardboard, metal, etc., (which although not used for printing purposes, for the sake of brevity in this description will be called "types"), in combination with a plane surface to form a background and support for the same, the types being provided on their back sides with convenient spikes for fastening them to the background, which may also be provided with convenient holes for receiving said spikes.

In the accompanying drawings illustrative of a convenient embodiment of the invention:

Fig. 1 shows a sign card composed of four types, of which the second large one and the second small one have been removed in order to show the holes in the background;

Fig. 2 is an elevational view looking toward the inner face of one of the characters;

Fig. 3 is a cross section of the arrangement shown in Fig. 1, and

Fig. 4 is a vertical sectional detail of a slightly modified form of the invention.

In all the above mentioned figures the same reference characters indicate like or corresponding parts.

The sheet *a* forming the background of the sign and support for the types, is perforated as indicated at *b*. These perforations *b* may be made for each occasion as required, or they may be permanently provided in horizontal and upright rows and at uniform distances apart, as shown in the lower right hand corner of Fig. 1. In the latter case the spikes on the back of the types will be at correspondingly uniform distances apart, which is not the case in the types shown in said figure.

The types *c* are provided on their backs with one or more spikes *d* of such diameter

as to fit tightly into the perforations *b* so that they have to be forced into the latter by a slight pressure in order that they may be held firmly therein. Generally speaking, the smaller sizes will have a single spike, and the larger one two or more as may be necessary. They may be of cylindrical or square section, tapering or not, a very convenient form being that shown in Fig. 4 of the drawings, in which the spikes are shown in the form of headed studs, thus permitting them to be easily introduced but firmly held in place when driven "home". For the same purpose the holes in the background sheet may be made tapering.

The lines of holes, instead of being straight may also be curved or fanciful in order to produce artistic effects in the sign or inscription.

The material for the types as well as for the background sheets may be metal, cardboard, celluloid or any adequate material. The background sheet may also be made of rubber, cork or like elastic material, in which case the type spikes may be sharp pointed and no holes will be necessary, as the spikes will enter easily and the holes close and become invisible after the spikes are retired therefrom.

Having thus described my invention what I claim and desire to protect by Letters Patent of the United States of America, is:

A changeable price sign of the character described including in combination, a relatively thin flexible plate provided with a plurality of small openings arranged equidistantly with respect to each other and in rows extending transversely and longitudinally of the plate, a plurality of changeable characters and headed spikes projecting outwardly from the inner faces of the characters at suitable distances from each other and corresponding to the distances at which the openings in the plate are spaced from each other and adapted to be sprung into engagement with the openings so as to securely yet detachably hold the characters on the plate, substantially as and for the purposes set forth.

Signed at Buenos Aires, Argentine Republic this 11th day of March A. D. 1924.

VICTORINO LORENZO.
